1 Claim

ABSTRACT OF THE DISCLOSURE

An apparatus for opening drums and the like comprising a bar having secured to one end thereof at least one transversely extending rod, and having the other end thereof serving as a handle, and at least one transversely extending hook-shaped member positioned intermediate the handle and the rod and lying in the same longitudinal plane as the rod.

BACKGROUND OF THE INVENTION

(1) Field of the invention

This invention relates to an apparatus for separating objects, and more particularly to an apparatus for opening cardboard drums which have the ends thereof pressed in or press-fitted.

(2) Description of the prior art

Heretofore, there has been no efficient way in which to open drums which have been constructed of compressed nonwovens or cardboard other than to use an axe or similar implement. The ends of these drums are usually press-fitted more or less rendering the entire drum an integral unit. Wedge bars, rip bars, wrecking bars, crowbars, etc., have proved ineffective due to (1) there being no fulcrum point upon which to predicate leverage, the material crushing under light loads, and (2) there being nothing in the form of a lip, etc. to obtain a hold.

The present practice of opening these drums with an axe is dangerous and presents a safety hazard. This is particularly the case when the drums contain slippery materials such as soap, etc. After one has opened a number of drums, his hands become slippery and the handle is hard to hold thus presenting the possibility of an axe flying across the room.

Further, when an axe is used to open the drums, a number of strokes are necessary which consume valuable time and inherently cut down on profits.

The above-mentioned tools are readily available, simple, and inexpensive, and any substitute therefor should also possess these qualities, even though safety would warrant the foregoing of some of these qualities. The apparatus of this invention possesses all of the above qualities and is completely safe to use.

Also, when the above tools, particularly the axe, are used the chances of tearing the sides of the drum and spilling the contents are great.

SUMMARY OF THE INVENTION

This invention overcomes the disadvantages pointed out above by providing an apparatus which is capable of obtaining a hold on the ends of drums in order that they may be easily removed, the apparatus having at least one transversely extending rod secured to one end of a bar, and having at least one transversely extending hook posi-

2

tioned and secured to the bar intermediate the rod and the other end of the bar.

It is therefore an object of this invention to provide a simple and inexpensive drum opening apparatus.

Another object of this invention is to provide an apparatus for separating objects which is safe to use.

Further, it is an object of this invention to provide a drum opening tool which will save time and enhance economies.

Yet another object of this invention is to provide a drum opening apparatus which is capable of opening drums without destroying their containing qualities and allowing the contents to spill out.

These and other objects and advantages will become more readily apparent when read in conjunction with the remainder of the specification and considered along with the accompanying drawing.

BRIEF DESCRIPTION OF THE DRAWING

20 The drawing shows a perspective view of a preferred embodiment of a drum opening apparatus according to this invention.

DESCRIPTION OF THE PREFERRED EMBODIMENT

25 The drum opening apparatus shown in the drawing is generally denoted by reference numeral 1, and is made up of an elongated straight bar 2 having one end serving as a handle 3. On the other end 4 of bar 2 is tangentially secured a plate 5 having perpendicularly extending pointed rods 6 secured thereto. Intermediate bar ends 3 and 4, a transversely extending hook-shaped member 7 is secured to bar 2 and lies in the same, or a parallel, plane with rods 6. Hook-shaped member 7 has a pointed end 8 extending in the general direction of end 4 of bar 2.

30 A brace 9 for reinforcing hook-shaped member 7 is secured, as by welding, to member 7 as at 11 and to bar 2 as at 10.

35 Deviations from the preferred embodiment described above are considered within the realm of this invention. For example, any number of rods 6 will suffice as long as there are at least one. Also, rods 6 may be secured directly to bar 2 thereby eliminating the need of plate 5.

40 Bar 2 can be a pipe, solid rod, etc., and can have end 4 flattened whereupon plate 5 will be unnecessary.

45 In operation, drum opening apparatus 1 is utilized opening cardboard drums by placing a point on bar 2 intermediate plate 5 and hook 7 on an edge of the drum and forcing hook 7 into the side of the drum. Hook 7 will puncture the drum just below where the lid fits onto the drum. Then by lifting the handle end 3, rods 6 will pierce the lid and same will be removed.

50 It will be appreciated that the apparatus of this invention can be used for opening drums, cartons, boxes, etc., and in general for separating objects.

55 The distance between the hook-shaped member and the rod will necessarily be less than one of the dimensions of the objects separated. For example, when the apparatus of this invention is used for removing tops from drums, the distance between the hook-shaped member and the rod will have to be less than the diameter of the tops.

60 The foregoing illustrates the essential features of the invention as well as some of the manners in which it may be practiced. Various changes and modifications may be made in practicing the invention without depart-

ing from the spirit and scope thereof, and therefore, the invention should not be limited except as defined in the appended claim.

We claim:

1. An apparatus for separating objects comprising:
  - (a) an elongated straight bar;
  - (b) a plate tangentially secured near one end of the bar;
  - (c) at least one perpendicularly extending rod secured to the plate; and
  - (d) at least one transversely extending hook-shaped member positioned intermediate the rod and the other end of the bar.
